VARIABLE PITCH PROPELLER

Ivan H. Driggs, Towson, Md., assignor to The
Glenn L. Martin Company, Baltimore, Md.

Application July 9, 1937, Serial No. 152,677

4 Claims. (Cl. 170—164)

This invention relates to propellers and more particularly to propellers of the variable pitch type.

Variable pitch propellers may be divided into two classes; namely manually operated and automatically operated. The latter class may be divided into two sub-classes; namely power operated and self operated, the latter being dependent upon the several forces acting upon the propeller during operation for automatically changing the pitch of the propeller blades, while the former is dependent upon some power force, such as hydraulic, electrical, and so forth.

Primarily the present invention has to do with the provision of a propeller construction which can be easily adapted for use with any of the above mentioned classes or sub-classes of variable pitch propellers.

Various and sundry types and forms of variable pitch propellers have heretofore been proposed, but the only types of variable pitch propellers known to me to have proven to any satisfactory degree of practicability are those of the power operated automatic type, such as the Hamilton Standard, which employs oil pressure for turning the blades, or the Curtiss electrically operated propeller. There has not been, to my knowledge, an automatic variable pitch propeller of the self operated type heretofore proposed that has proven to be practical and it is one object of this invention to provide a propeller construction of the self operated automatic type that shall not only be theoretically sound, but practical in operation.

It is another object to provide a propeller construction that shall be practical and readily adaptable for use as a manually operated variable pitch propeller or a power or self operated automatic variable pitch propeller.

Another object is to provide a propeller construction of the automatic type that shall consist of a minimum number of relative movable parts.

A further object is to provide in a propeller of the variable pitch type novel means for adjusting the pitch of the propeller blades that shall be simple, rugged, durable, and comparatively inexpensive to manufacture.

A still further object is to provide in a propeller of the variable pitch type novel means for connecting the propeller blades to a propeller hub in such a manner as to cause the several forces acting upon the blades during operation to automatically provide the desired pitch during all operating conditions.

The above and other objects will be made apparent throughout the further description of the invention when taken in connection with the accompanying drawings, wherein like reference characters refer to like parts. It is to be distinctly understood that the drawings are not a definition of the invention but merely illustrate certain forms of the invention, by means of which the invention may be effectuated.

In the drawings:

Figure 1 is a front elevational view, more or less diagrammatic, of a propeller together with the associated power mechanism embodying one form of the invention.

Figure 2 is a side elevational view of the embodiment shown in Figure 1, illustrating in broken lines a position which the propeller may assume under certain conditions.

Figure 3 is an enlarged fragmentary sectional view taken along the line 3—3 of Figure 1.

Figure 4 is a fragmentary view showing two positions of the propeller blade.

Figure 5 is a side elevational view of a propeller, illustrating another embodiment of the invention.

Figure 6 is a front elevational view similar to Figure 1, illustrating still another embodiment of the invention.

Figure 7 is a side elevational view of the embodiment shown in Figure 6, and

Figure 8 is a fragmentary sectional view, more or less diagrammatic, showing a power means for changing the pitch of propeller blades embodying the invention, which may be either manually or automatically operated.

Referring to the drawings, Figures 1 to 4, inclusive, illustrate a preferred form of the invention, wherein the propeller is of the self operated automatic type. This embodiment consists of a power shaft 10, driven by the power plant represented in its entirety by 11, a novel propeller hub 12 fixedly mounted on the shaft 10 and adapted to be driven thereby, the hub 12 being adapted to accommodate a pair of blades 13. One form of the present discovery resides in the manner in which the blades 13 are hingedly connected to the hub 12 as shown at 14. As is apparent from the drawings, each of the blades 13 is hingedly connected to the hub 12 in such a manner that the axes of the associated hinges 14 lie in the plane of rotation of the blades 13, the axes of the hinges being disposed at an angle of less than ninety degrees with the axes or chords of the associated propeller blades.

The operation of this construction may be illustrated thusly: the arrow 15 in Figure 1 indicates the direction of rotation of the propeller blades. 16 and 17 indicate the leading and trailing edges, respectively, of the blades 13. Immediately upon applying power to the shaft 10, the air thrust acting upon the blades 13 will tend to turn them forwardly about their respective axes or hinges 14 as shown at 18 in Figure 2. Because of the inclination of the axes 14, the trailing edges 17 of each of the propeller blades will travel a greater linear distance than the leading edges 16 of the blades, thereby changing the pitch of the blades, and in the particular instance just described, the pitch of the blades is reduced. It follows that upon reducing the pitch of the blades that the load on the motor or power plant 11 is reduced, at which time the power plant having comparatively light load thereon readily speeds up to provide the desired propeller revolutions, during which time the centrifugal force developed by the rotation of the blades tends to move the blades backwards about their respective hinges 14 and toward and into the plane of revolution of the propeller. Inasmuch as the trailing edges of the propeller blades will travel a greater linear distance than the leading edges as above pointed out, it follows that the pitch of the propeller blades will be increased as the blades are moved rearwards under the action of the centrifugal force.

For the purpose of this application, the term propeller thrust is defined as the action of the propeller blades upon the surrounding air to effect the movement of the propeller forwardly through the air. Now, with this explanation, there are two forces operating oppositely one to the other upon the propeller blades, which may be better stated thusly: the propeller thrust is at all times tending to decrease the pitch of the propeller blades, while the centrifugal force developed by the rotation of the propeller tends at all times to increase the pitch of the propeller blades. With this understanding it will, of course, be understood that in the construction of propellers of different sizes and for different duties, the weight of the blades as well as the angle at which the blades are hingedly connected to the hub must be determined to suit the specific installation concerned.

Figure 3 merely shows spring-held members 21 employed for limiting the turning movement of the blades 13 about the hinges 14 and likewise to effect a cushioned stop for the blades at their extreme limits of turning about the hinges 14.

Figure 4 illustrates a front elevational view of one of the blades 13 illustrated in Figures 1 and 2. The primary purpose of this figure is to illustrate that the blade 13, in turning about its axis 14, does not only move forwardly and rearwards relative to the plane of revolution of the propeller, but that the blade simultaneously moves laterally with respect to the plane of revolution.

Figure 5 illustrates another embodiment of the invention, wherein the blades 13 are hinged about axes 14, the latter, while each being disposed at an angle of less than ninety degrees with the axis or chord of the corresponding propeller blade, each is disposed in a plane at substantially right angles to the plane of revolution of the propeller. In this embodiment the pitch of the blades is subject also to two opposing forces; namely, centrifugal force developed by the rota-

tion of the blades similar to that described in connection with Figures 1 and 2 in that in the specific form shown the centrifugal force tends to increase the pitch of the blades. The other force is here defined as propeller drag and that is the resistance that the air sets up to the rotation of the propeller blades. This propeller drag tends to turn the blades about the axes 14 in a direction opposite to the direction of rotation of the propeller. This tendency is directed toward decreasing the pitch of the blades. This feature results in the fact above stated that the trailing edges 17 of the blades travel a greater linear distance than the leading edges during a given movement of the blades about their axes 14. Here the pitch of the propeller blades is responsive to the opposing forces, of propeller drag and centrifugal force of the blades.

Figures 6 and 7 illustrate still another embodiment of the invention, wherein the blades 13 are hingedly connected to the hub 12 in an intermediate position between the positions illustrated in Figures 2 and 5. In this form the pitch of the propeller blades is responsive to the centrifugal force developed during the rotation of the blades and the resultant forces of the propeller thrust and propeller drag acting on the blades, the resultant forces, namely the propeller thrust and propeller drag, tending to decrease the pitch of the blades, while the centrifugal force developed by the rotation of the blades tends to increase the pitch of the blades.

Figure 8 is a fragmentary sectional view through a power shaft 10, more or less diagrammatic, illustrating a hydraulic or oil pressure mechanism for moving the blades 13 about the axes 14. The root or inner ends of the blades 13 in this embodiment are of slightly different construction than those shown in the other embodiments and provide shoulders 22 on each side of the inner ends of the blades 13 for cooperating with power operated lugs 21a. These power operated lugs 21a differ from the cushioned stops 21 illustrated in Figure 3 in that they are connected with a hydraulic system represented in its entirety by 23, whereby each of the lugs 21a is carried by a piston 24 positioned in a cylinder 25. These lugs 21a are simultaneously actuated in opposite directions through the conventional valve mechanism illustrated at 26, the latter may be operated either manually or automatically by any conventional means for supplying oil from a source by way of pipes 27 or 28 dependent upon the direction that the propeller blades are to be turned about their axes 14.

Accordingly, I have provided a propeller construction which may be adaptable for use as a manually operated propeller as well as an automatic variable pitch propeller of either the power operated or self operated type.

Some of the important features of the invention are that the pitch of the propeller blades may be either manually or automatically varied to provide maximum operating efficiency during taking off, climbing, high altitudes, and other conditions; when operating self acting, the bending stresses throughout the length of the blades in a direction normal to the plane of rotation will be materially reduced, while at the hub, the bending stresses will be absolutely zero due to the hinged joints; the weight of the blades will be materially reduced and the factor of safety greatly increased in view of the reduction of the above mentioned bending stresses, and for the

same reason thinner and more efficient airfoil sections may be employed; the type of flexural vibrations now present in propellers will probably be eliminated due to the fact that the 5 blades have perfect freedom of movement; the vibration in the blades caused by irregularities of air flow through the propeller disc caused by the presence of a wing or unsymmetrical nacelle behind it will be eliminated, since the blades can 10 adjust themselves immediately to the local conditions of air flow.

While the several forms of the invention have been described in connection with a two bladed propeller, it is to be distinctly understood that 15 the invention may be utilized in a propeller having any number of blades. It is to be further understood that the teachings of the invention may be utilized by positioning the hinge axes in some other plane or angle than those specifically illustrated here. One of the primary 20 purposes of showing the different embodiments in this application is to teach that the invention may be employed in various forms of construction without departing from the spirit and scope 25 of the invention. The invention is defined by the appended claims.

I claim:

1. A screw propeller comprising a plurality of blades and a hub having an opening therein 30 adapted to receive a drive shaft, a hinge transversely inclined with respect to the longitudinal axis of said shaft connecting each blade to said hub, oppositely extending shoulder portions on opposite sides of each of said blades adjacent

said hinge, and a hydraulic control means operatively engaging each of said portions for changing the pitch of said blades by turning each blade on its hinge.

2. A screw propeller comprising a plurality of 5 blades each of which has opposed elements transversely extending from said blades, a hinge for each of said blades, a hub, and hydraulic means for changing the pitch of each of said blades, said hub having an opening adapted to receive a 10 drive shaft, each hinge having its longitudinal axis transversely inclined with respect to the longitudinal axis of said opening, and each hydraulic means consisting of a hydraulically operated lug cooperatively engaging each of said elements upon each of said blades to change the 15 pitch of each blade by its rotation about its hinge.

3. A screw propeller as in claim 2, a hollow 20 drive shaft in said opening in said hub, feed lines for supplying fluid to said hollow shaft, 25 and individual piston means communicating with said hollow shaft and operatively connected to each of said lugs.

4. A screw propeller comprising a plurality of 30 blades each of which has opposed lugs and a hub having an opening therein adapted to receive a drive shaft, a hinge connecting each blade to said hub and having its axis transversely inclined with respect to the longitudinal axis of said opening, and a hydraulic control means engaging each of said opposed lugs of each blade for turning each blade on its hinge to adjust the pitch of said blade.
